DESIGN FOR A CARPET SWEEPER

Abraham Fineberg, Detroit, Mich.

Application August 10, 1936, Serial No. 64,335

Term of patent 3½ years

To all whom it may concern:

Be it known that I, Abraham Fineberg, a citizen of United States and a resident of Detroit, Michigan, have invented a new, original, and ornamental Design for Carpet Sweepers, of which the following is a specification, reference being had therein to the accompanying drawing forming a part thereof.

Fig. 1 is a plan view of a carpet sweeper showing my new design;

Fig. 2 is a front elevational view;
Fig. 3 is an end elevational view; and
Fig. 4 is a perspective view thereof.

The handle of the sweeper is shown in a fragmentary condition for convenience of illustration.

What I claim is:

The ornamental design for a carpet sweeper, substantially as shown and described.

ABRAHAM FINEBERG,
